ADHESIVE APPLYING DEVICE

Melville W. Clement, Jamestown, N. Y., assignor
to Howard G. King, Jamestown, N. Y.

Application November 29, 1938, Serial No. 242,982

7 Claims. (Cl. 91—51)

This invention relates to an improvement in devices for applying a liquid adhesive to sheet or strip material.

The disclosed form of the invention is adapted to apply a liquid adhesive to a marginal portion of one face of material in sheet or strip form. The device may be either manually or mechanically operated to feed the material therethrough and provides means for varying the quantity of adhesive that may be applied to the material.

Prior to this invention it has been the practice to apply an adhesive to sheet or strip material through the use of a brush or special cap on an adhesive container. In some instances the material is treated with a quick drying adhesive that can only be used upon the application of moisture. In many business organizations it is frequently necessary to superpose printed or other forms upon contracts or other memoranda. Because this is not a general requirement, it is unnecessary to have all forms prepared with an adhesive marginal portion and, therefore, it becomes advantageous to apply a coating of adhesive to a sheet or strip as and when it is desired to permanently mount the sheet or strip.

The present invention has been developed for the purpose of providing a device for applying an adhesive to sheet or strip material, and this, therefore, constitutes one of the objects of the invention.

Another object of the invention lies in the provision of a device for applying a liquid adhesive to a marginal portion of sheet or strip material.

Another object of the invention lies in the provision of a device for applying an adhesive to sheet or strip material in which adjustment may be made to vary the amount of adhesive to be applied.

Another object of the invention lies in the provision of an adhesive applying device having means for maintaining a sheet or strip in contact with an adhesive applicator during movement of the sheet or strip through the device.

Other and further objects and advantages of the invention will be more fully understood from a consideration of the following specification taken in conjunction with the accompanying drawing; and in which

Figure 1 is a plan view with parts broken away of one modification of an adhesive applying device;

Figure 2 is a side elevation of the structure shown in Figure 1;

Figure 3 is a vertical sectional view, taken substantially on the line 3—3 of Figure 1;

Figure 4 is an enlarged fragmentary vertical sectional view with parts broken away showing the means by which sheet or strip material is held in contact with an adhesive applicator; and

Figure 5 is a vertical sectional view, taken substantially on the line 5—5 of Figure 1.

Figure 6 is a fragmentary vertical sectional view, taken substantially on line 6—6 of Figure 4, and discloses means for disengaging the material from the feed roller.

Reference is now had to the drawing wherein the numeral 10 is employed to designate, in general, one modification of a device for use in applying a coating of adhesive to sheet or strip material. The device comprises a rectangular box-like structure 10 having a front wall 11, rear wall 12, and side walls 13 and 14. A plate 16 covers the top of the device and forms a work receiving surface. To provide adequate surface for receiving sheet or strip material, the plate 16 may be of such proportions as to overhang the front wall 11 of the device. Adjacent the rear of the device, an opening or slot 17 is made transversely of the plate 16. Mounted in any suitable manner, as by bearings 18 located in the side walls 13 and 14, is a shaft 19. This shaft serves to mount a roller 21 that, for convenience, may be separated into several roller surfaces by the provision of annular grooves 22. Located within the device is an adhesive reservoir 23. One end of the reservoir may be mounted on a bracket 24 and the other end secured to the wall 13 along a flange 26, by means of a screw 27. Mounted on the shaft 19, between one end of the roller 21 and the wall 13, is an adhesive applicator 28 that is in the form of a roller. This roller, in the present disclosure, is of substantially the same diameter as roller 21 and at all times a portion thereof is within the reservoir 23. The rollers 21 and 28 project above the plate 16 through the opening 17 provided therefor.

Secured to the inner face of the plate 16, adjacent the circumferential edge of the roller 28, is a bracket 29. The bracket 29, through a pin 31, pivotally supports one end of an arm 32. The other end of the arm is forked and adapted to receive the circumferential edge of the roller 28 in the space thus formed. One end of a shaft 33 is joined to the arm 32. The other end of this shaft projects through the front wall 11 and is fitted with a suitable knob 34. A bracket 55

36, secured to the wall 11, has an opening through which the shaft 33 projects. Threads on the shaft and in the walls of the opening of the bracket prevent longitudinal movement of the shaft 33 in any manner except by rotation. A lock nut 37, mounted on the shaft 33, serves to prevent inadvertent rotation thereof and consequent axial movement.

Above the plate 16 is a guide roller supporting member, generally indicated by the numeral 38. The member 38 includes a plate 39 that is arranged transversely of one end of the device. The end 40 of the plate, located adjacent the roller 28, is provided with one or more vertical flanges 41 that project downwardly through a suitable opening in or adjacent one edge of the plate 16 and are secured in any suitable manner to the rear and side walls 12 and 13 of the device. Adjacent the end 40, the plate 39 is formed with slots 42, the corresponding walls 43 of which serve to pivotally mount the upper ends of a pair of arms 44 and 46. A further pair of arms 44 and 46 are pivotally joined to the free end 47 of the plate 39. As may be seen from the drawing, arms 46 are straight, being suspended adjacent the rear of the plate 39. These arms serve to carry a shaft 48 located beneath the front of the plate 39. Arms 44 are suspended at the front edge of the plate 39 in the same plane as arms 46 and are formed with centrally offset portions 49 for this purpose. The lower ends of arms 44 carry a shaft 51 located adjacent the rear of the plate 39. Mounted on each of the shafts 48 and 51 are spaced apart rollers 52. Adjacent the lower ends of arms 44 and 46 are pins 53. These pins are engaged by springs 54 that normally urge the rollers 52 downwardly into positive contact with the roller 21.

40 In the present modification, three rollers 52 are positioned on each of the shafts 48 and 51. Between corresponding rollers of each shaft is located a shoe 56. The shoe is formed with a central portion that is adjacent and generally conforms to the contour of the roller 21. The shoe is formed with upwardly curved ends 57 that extend over the plate 16 of the device. Each shoe is carried by one or more rods 58 that are threaded into the plate 39. Lock nuts 59 serve to prevent displacement of the shoes 56 and at the same time permit vertical adjustment thereof.

Having described the structural features of the invention, the operation thereof is as follows. It is assumed that a liquid adhesive has been placed in the reservoir 23. A sheet or strip of material 61 is placed on the plate 16 adjacent a guide bar 62. The material is moved along the plate until the front edge thereof projects beneath the forward ends 57 of shoes 56 and contacts the meeting surfaces of rollers 21 and 52. Any suitable means may be employed to rotate roller 21, such, for example, as a crank 63, which is secured to an extension of the shaft 19. Rotating the shaft 19 causes rollers 21 and 65 52 to rotate, feeding the material 61 over roller 21 and beneath shoes 56. The adhesive applicator roller 28 is rotated simultaneously with the rotation of roller 21 and having accumulated a quantity of adhesive, transfers it to the material. The adhesive applied to the material is of uniform thickness due to the forked end of arm 32. The thickness of the adhesive layer may be varied by rotating knob 34, which, through shaft 33, adjusts arm 32 toward or away 70 75 from the roller 28. Thus, when the adhesive

coated roller 28 comes into contact with the under surface of the material 61, only a desired amount of adhesive is applied to said material.

It will be noted that lugs 64 are provided on the plate 16. These lugs are inclined upwardly and project into grooves 22 of the roller 21. Their purpose is to strip the material from the roller 21 following application of the adhesive.

It will be understood that the applicator may be of different proportions than shown and may 10 be located other than adjacent one side of the device for the purpose of applying an adhesive to any other part of the material 61. Furthermore, it will be noted that through the provision of the floating rollers and shoes the material is at all times caused to follow a definite and predetermined path through the device during 15 the process of applying the adhesive.

Although applicant has shown and described only one modification of his invention, it will 20 be understood by those skilled in the art that other modifications and adaptations thereof may be made without departing from the spirit and scope of the invention as defined in the hereunto annexed claims.

Having thus set forth my invention what I claim as new and for which I desire protection by Letters Patent is:

1. A device for applying an adhesive to flexible material comprising a support, an adhesive reservoir, a rotatable applicator projecting into said reservoir, a feed roller in said device, guide shoes positioned above said roller, means causing the material to contact said roller and said applicator, said means being interspaced with 35 said shoes, and further means for simultaneously rotating said roller and said applicator whereby to move the material through said device and progressively transfer adhesive from said applicator to the material.

2. A device for applying an adhesive to flexible material comprising a support, an adhesive reservoir, a rotatable applicator projecting into said reservoir, a material receiving top on said support, a feed roller in said device projecting through a suitable opening in said top, guide means located above and adapted to direct said material onto said feed roller, floating rollers interspaced with said guide means serving to contact the material with said feed roller and said applicator, said feed roller and said applicator being rotatable to move the material through said device and transfer adhesive thereto.

3. A device for applying a liquid adhesive to flexible material comprising a support, an adhesive reservoir carried by said support, a rotatable shaft in said support, a feed roller and applicator carried by said shaft, said applicator projecting into said reservoir, sets of rollers above said feed roller, adjustable guide means interposed between corresponding rollers of said sets, said rollers and said means serving to contact the material with said feed roller and said applicator, and means for rotating said shaft whereby to move the material through said device and apply an adhesive coating thereto.

4. A device for applying a liquid adhesive to flexible material comprising a support, an adhesive reservoir carried by said support, a rotatable shaft in said support, a feed roller and applicator carried by said shaft, said applicator projecting into said reservoir, sets of spaced apart rollers adjacent said feed roller, guide

- shoes interposed between corresponding rollers of said sets, spring urged means mounting said rollers for pressure contacting the material with said feed roller and said applicator, means movable into immediate proximity with said applicator serving to vary the quantity of adhesive taken on by said applicator, and further means for rotating said shaft.
5. In a device for applying liquid adhesive to flexible material, a support, an adhesive reservoir carried by said support, a rotatable shaft in said support, a feed roller and applicator carried by said shaft, said applicator projecting into said reservoir, two sets of rollers, means suspending 10 said sets of rollers above said feed roller, said sets of rollers being engageable with said feed roller under pressure produced at least in part by the weight of said sets of rollers, said sets of rollers being so positioned as to produce a slight 15 wrap around of said flexible material on said feed roller and said applicator when said material moves through said device by rotation of said feed roller.
6. In a device for applying a liquid adhesive to flexible material, a support, a feed roller and adhesive applicator mounted on a shaft in said support, a plate above said roller, depending arms pivotally connected with said plate, shafts 20 carried by said arms, spaced rollers on each of

said shafts, the rollers on each shaft being in close proximity with and caused at least in part to contact the upper surface of said feed roller by force of gravity said roller serving, when material is fed through said device, to produce a slight wrap around of said material on said feed 5 roller.

7. In a device for applying a liquid adhesive to flexible material, a receptacle member, an adhesive reservoir in said member and having exterior connection for manual removal thereof, a feed roller on said shaft, an adhesive applicator roller on said shaft adjacent one end of said feed roller, said applicator roller projecting into said reservoir, a plate extending transversely 15 of and positioned above said member, pairs of arms pivotally connected at opposite ends of said plate, the arms of each pair being crossed, shafts carried by corresponding pairs of said arms, spaced apart rollers on said shafts, guide means 20 depending from said plate, said guide means being interposed between the spaced apart rollers and in close proximity with a portion of said feed roller, the rollers carried by said shafts cooperating with said guide means to contact said 25 material with said feed roller and said adhesive roller.
